DISPLAY DEVICE FOR SHOP WINDOWS

Stefan Belobrajdech, Milwaukee, Wis.

Application June 24, 1937, Serial No. 150,096

2 Claims. (Cl. 40—33)

This invention appertains to a novel display device, and more particularly to an animated shop window display for various articles of merchandise.

5 One of the primary objects of my invention is to provide a device which will readily fit into a shop window for displaying merchandise in an attractive and novel manner, whereby the attention of prospective purchasers will be directed 10 thereto.

Another salient object of my invention is to provide a window display embodying a series of members for receiving the merchandise, with means for synchronously rotating said members, 15 whereby not only will the attention of passers-by be attracted thereto, but whereby all sides of the merchandise will be shown.

A further object of my invention is to provide 20 novel means for mounting the displayed members on a central support, whereby said members can be adjusted to various positions to vary the display and to further the particular characteristics of the merchandise being shown.

A still further object of my invention is to provide 25 a novel window display of the above character, which will be durable and efficient in use, one that will be simple and easy to manufacture, and one which can be placed upon the market at a reasonable cost.

30 With these and other objects in view, the invention consists in the novel construction, arrangement, and formation of parts, as will be hereinafter more specifically described, claimed, and illustrated in the accompanying drawings, in 35 which drawings:

Figure 1 is a fragmentary rear elevation of my improved window display, with parts of the cover for the base member shown removed.

Figure 2 is a fragmentary top plan view of the 40 window display, with the supporting standards in section.

Figure 3 is a horizontal section taken substantially on the line 3—3 of Figure 1, looking in the direction of the arrows.

45 Figure 4 is an enlarged detail elevation of the current-conducting means for the central standard, the wiring for said central standard being shown diagrammatically.

Referring to the drawings in detail, wherein 50 similar reference characters designate corresponding parts throughout the several views, the letter D generally indicates my improved window display, which, as shown, includes a centrally disposed base 10, which can be of a pyramidal shape.

55 This base 10 includes a framework 11, to

which can be removably secured side plates 12. Rotatably supported by the base 10 is an upright standard 13, which is adapted to support any preferred means for holding or displaying merchandise. As suggested in dotted lines in Figure 1, 5 the standard can be provided with a series of graduated shelves 14.

Rigidly mounted upon the upper end of the standard is a supporting platform 15, on which can be mounted any desired number of sockets 16 for lamp bulbs 17. The platform 15 can carry a shade for housing the bulbs. The particular means employed for conducting current to the sockets 16 will be later set forth.

Extending laterally from the opposite sides of 15 the base 10 are side wall plates 18 and 19, and these plates carry the side displays, as will now be set forth.

Each side display comprises a supporting arm 20, which is adjustably mounted on the rear face 20 of its side wall plate. As illustrated, the arm 20 is pivotally mounted intermediate its ends on a bolt 21, which carries a winged nut 22 for binding engagement with the arm to hold the same in an adjusted position.

To limit the swinging movement of the arm on the bolt 21, the arm can be provided with an arcuate guide slot 23, through which extends a guide pin 24 carried by the side wall plate. Arranged upon the arm 20 is a supporting bracket 30 25, and this bracket is also mounted for adjustment. Thus, the same is rockably mounted intermediate its ends on a bolt 26 carried by the arm 20, and the bolt in turn has threaded thereon a winged nut 27 for binding engagement with 35 the bracket. The bracket is limited in its swinging movement by a pin 28 on the arm, which extends through a slot 29 in the bracket.

The outwardly extending portion of the bracket carries a platform 30, and this platform is provided with a suitable bearing for a rotatable standard or shaft 31. This side standard or shaft 31 is provided with any desired type of shelves or the like for supporting the merchandise which is to be displayed.

45 The platform 30 can be moved in or out on the bracket, and the inner end thereof is preferably bifurcated, as at 32, for straddling a tightening bolt 33 on the bracket. By this arrangement, it can be seen that the arm 20, the 50 bracket 25, and the platform 30 can be adjusted to various positions. This will permit the changing of the display form and permit the device to be adjusted to particular types of windows.

Both the central shaft or standard 13 and the side standards or shafts 31 are driven from a single electric motor 34, which is preferably disposed within the hollow base 10. The motor 5 can be mounted upon a strap 35, which can be secured to the framework 11 of the base. The armature shaft of the motor has keyed or otherwise secured thereto a pinion 36, which meshes with a gear wheel 37 rigidly secured to the central shaft. This central shaft 13 has secured thereto 10 a pair of pulley wheels 38 and 39, around which are trained oppositely extending pulley belts 40 and 41, which lead toward the side displays.

Adjustably mounted on the side wall plates 18 15 and 19 are adjustable arms 42, which carry stub shafts 43 having keyed or otherwise secured thereto pulley wheels 44 and 45. The belts 40, and 41 are trained about the pulley wheels 44, and the pulley wheels 45 have trained about the 20 same drive belts 46, which are placed about pulley wheels 47 carried by stub shafts 48. These stub shafts 48 are carried by the upper ends of the arms 20, and the stub shafts also carry pulley 25 wheels 49, around which are placed pulley belts 50 leading to pulley wheels 51, which are keyed or otherwise secured to the side standards or shafts 31.

By this arrangement of parts, it can be seen 30 that all of the standards or shafts are rotated from a single motor.

The arms 42 are made adjustable so that the 35 position of the pulley belts 41 and 46 can be changed to agree with the positions of the arms 20 and the brackets 25. Each arm 42 is provided with a longitudinally extending slot 52, through which extends a guide pin 53 and a 40 tightening bolt 54. The pin and bolt are carried by the side wall plates, and, obviously, by tightening the bolt the arm 42 can be held in its 45 preferred raised or lowered position.

Other displays can be utilized with the device 45 when necessary or desirable, and these additional displays can take the form of boards 55, which rotatably support at their terminals shafts 56. The shafts 56 carry shelves or the like for the 50 goods to be shown, and these shafts have rigidly secured thereto pulley wheels 57. Pulley belts 58 are adapted to be trained about the pulley wheels 57 and over pulley wheels 59, which can be secured to the central shaft 13. There can be as many of the pulley wheels 59 as may be desired.

Any number of the boards 55 can be utilized, 55 and the same are adapted to extend through notches 60 formed in the base 10, and the base can also be provided with openings 61, through 60 which the pulley belts 58 can extend. The inner ends of the boards 55 can be notched, so that the same can fit tightly against a base plate 62 rigidly secured in the base 10. The boards 55 can be made in sections telescopically connected, whereby the boards can be lengthened or shortened.

In order to convey current to the sockets 16 65 during the rotation of the shaft or standard 13, I provide contact brushes 63 and 64, which are connected by means of wires 65 and 66 to the opposite sides of a battery 67 or other source of power.

It is proposed to utilize house current where the same is available, and the base 10 can carry suitable sockets wired respectively to the motor and the brushes, whereby plugs can be utilized for connecting the sockets with the said house 5 current.

The lower brush 64 is in constant engagement with a contact disc 68 secured to but insulated from the pulley wheel 39. The pulley wheel 38 carries any preferred number of sector-shaped 10 contact plates 69, which are insulated from one another and from the pulleys. The brush 63 is adapted to successively engage the sector-shaped contact plates 69.

The plates 69 each have connected therewith 15 a terminal post 70, and the base of each lamp socket 16 is connected to one terminal post. All of the other contacts of the lamp sockets can be electrically connected to a common wire 71, which can lead to a terminal post 72, which is electrically connected with the contact disc 68.

Obviously, during the rotation of the central shaft or standard 13, the lamps 17 will be caused to flash on and off, due to the successive engagement of the brush 63 with the sector plates 69.

The various operating parts of the display can be hid from the view of observers by any desired type of ornamental housings, which have not been shown in the present instance, due to the 25 various forms which these housings can take.

From the foregoing description it can be seen 30 that I have provided a novel display device for shop windows, which will effectively attract the attention of persons passing by the window.

Changes in details may be made without departing from the spirit or the scope of my invention, but what I claim as new is:

1. A display device for shop windows comprising, a base member, a centrally disposed shaft carried by the base member and extending a material distance above the base member, display means for merchandise carried by the shaft, laterally extending side wall plates secured to the base member, adjustable arms on the side wall plates, adjustable brackets on said arms, rotatable shafts carried by the brackets, merchandise display means carried by the last-mentioned shafts, a motor having a direct drive engagement with the central shaft, and means for driving the side shafts from the central shaft including 40 pulley wheels and belts.

2. In a display device for shop windows, a base, a rotatable shaft carried by the base, a motor for rotating the shaft, a laterally extending side wall plate on the base, a swinging arm on the side 55 wall plate, means for holding the arm in an adjusted position against movement, a swinging bracket on the arm, means for holding the bracket in an adjusted position, a platform slidably mounted on the bracket, a side shaft rotatably carried by the bracket, a pulley wheel on the arm, a pulley wheel on the side shaft, a pulley belt connecting said pulley wheels together, a pulley wheel adjustably mounted on the side wall plate, means connecting the last-mentioned pulley wheel with the first-mentioned pulley wheel, and means for driving the last-mentioned pulley wheel from the central shaft.

STEFAN BELOBRAJDECH.
